UNITED STATES PATENT OFFICE.

WILLIAM HOFFMAN, OF BOSTON, MASSACHUSETTS.

GAME-BOARD.

SPECIFICATION forming part of Letters Patent No. 519,041, dated May 1, 1894.

Application filed September 12, 1893. Serial No. 485,319. (Model.)

To all whom it may concern:

Be it known that I, WILLIAM HOFFMAN, a resident of Boston, in the county of Suffolk and State of Massachusetts, have invented certain new and useful Improvements in Game-Boards; and I do hereby declare the following to be a full, clear, and exact description of the invention, such as will enable others skilled in the art to which it pertains to make and use the same.

The invention relates to a puzzle or game and has for its object to provide means for solving or playing the same; and it consists in the construction hereinafter described and particularly pointed out.

In the accompanying drawings Figures 1 and 2 are respectively a plan and central section of a board constructed according to the invention, the section being on line $x-x$ of Fig. 1. Figs. 3, 4, 5, and 6 are also plans of boards illustrating the improvement.

Referring to Fig. 1, numeral 1 indicates a board; and letters a, b, c, d, e, f, g and h indicate lines marked or formed in said board. These lines by preference are arranged in the form of concentric circles in order that the ending of one game shall leave the markers in position for the beginning of another. In said lines, places or stations for markers such as holes 1, 2, 3, &c., adapted to receive pins as 9', 10', 11', 12', 13', 14', 15' and 16' are provided. These markers or indicators which are not necessarily in the form of pins are equal in number to the lines. The holes, stations or places to receive the marker suitably arranged upon imaginary lines would suffice for the object of the invention though distinctly marked lines are preferred for the reason that they guide the eye when it is desired to move the markers or indicators from one station to another.

At a convenient part of the board each line, whether real or imaginary, and whether straight or curved, is provided with a single number arranged adjacent to others as shown at 9' to 16' in Fig. 1. This group of stations one in each line consisting of the highest numbers in the lines constitutes the home. The part of the board in which these numbers are situated and the markers grouped at the commencement of the game will be denominated "home." In the drawings the

pins are shown in their initial position or at home.

Several suitable series of numbers might easily be indicated upon a single board. But I have preferred to indicate a single series for each board and I illustrate several boards with appropriate numbers which differ in intricacy and interest. Each line or circle is provided with a number of holes or stations equal to the units in the home number of the particular circle. Thus the circle or line in which the home number 9' is situated will have nine holes or stations which may be numbered 9 to 1 in succession. The other circles are similarly numbered, the total number of holes in each equaling its home number as stated. The number of the stations in the several lines as herein set forth vary in order to avoid too great simplicity and provide for a larger number of moves necessary to win within the rules of the game. Were the same number employed in each line as for example if the numbers 8, 8, 8 were appropriated to three lines the first player would only have to understand that if his first move carries his marker to its home thereby exhausting for the purposes of that game one number 8 then thereafter he has only to imitate his opponent's move up to the next to the last move to win. Thus starting with 8, 8, 8 and the first player exhausting one 8 with his first move, if the second player moves either to 7, 6, 5, 4, 3 or 2 the first player has simply to do the same to win.

The board may be made of any desired material and outline and so also the markers; and the stations may be variously indicated.

The game is played by the aid of said board by two persons. The pins are placed in their initial or "home" positions as shown in the drawings, and they are moved round about their circles starting from left to right in the direction of the decreasing numbers, and as cards are dealt in whist, until they again arrive at home whence they are not thereafter moved during the pending game. The players move alternately, and each move involves the selection of one marker and the moving of it forward, on its own circle, to any desired station to and including the home station but not beyond the latter.

The end and aim of the game is to compel

an opponent to make the last move home. This can be done by a skilled player with entire certainty if he has once in the pending game obtained a winning position. To recognize a winning position and to move without taking any other is the object of the game.

The board shown in Fig. 5 will usually be preferred, as being neither too complex nor too simple a form of this puzzle. The board, Fig. 1, will be too intricate for popular use and boards might be constructed too simple for ordinary use.

It is desirable to arrange the stations in groups for convenience in selecting any one to receive a marker when moved. To secure a comparatively equal distribution of the numbers of such groups the stations are situated in parallel lines.

Let it be noted that the simple object of a player is to compel his opponent to make the last move. If in the progress of a game there are but two remaining possible moves obviously the first subsequent player wins, and if but three moves must be made and three only can be made then the first to play must lose. Skillful playing requires the foreseeing of these final situations and of the moves required to force an adversary into a losing position such as just noted. There are positions which enable the skillful player to do this with certainty. The home numbers or positions indicated in Figs. 1 to 6 inclusive are losing positions in the sense that the first to play can certainly win the game.

To further illustrate the use of the board, let it be assumed that the game has progressed to a point where the moves of all but three markers have been exhausted and where these three have each but one move remaining. It is obvious that the player whose turn it is to move in such case must lose the game since he can make no move that will compel his opponent to make the final move. Again, let it be assumed that the moves of all but two markers have been exhausted and that these have each but two possible moves remaining. Then the first to play must lose the game since he can make no move that will not obviously lose him the game on his next following move. The difference in the figures is based upon the differing mathematical aspects of the game. The mathematical problem involved divides itself into degrees of differing intricacy; Fig. 1 illustrates the fourth degree in full, while Fig. 5 illustrates the third degree in full; and Figs. 3 and 4 each illustrate the fourth degree in part, while Fig. 6 illustrates the third degree in part.

Boards might be made having upon them any of the many possible haphazard and irrelevant combinations of numbers, and the rules for playing this game might be applied to such boards, but it is the main province of my board to supply for the player positions that are peculiar to the game and, moreover,

those very rare positions that are best adapted for its purposes, *i. e.* the positions that produce the best features of the game, within the limit of the number of numbers employed, and within the limit of the highest of the numbers employed; as where four numbers are employed the highest of which is eight; or where three numbers are employed of which the highest is sixteen.

My invention does not cover haphazard combinations of numbers but only series between any desired proximate powers of the number 2 and preferably including the highest of said powers, and such series in combination with a separate line for each number each line having stations equal in number to the units of the serial number.

Each of my boards 1 to 6 inclusive is so designed and constructed that the key move produces the most interesting position in its degree, while it at the same time is the one move that to the unskilled player appears to be the least promising. The use of my board leads to certain rare positions from which may be obtained all possible phases of the game that lie within the limits of their numbers and their highest numbers. For instance, there are many four number positions which have eight as their highest number but they all, excepting five, six, seven and eight, make an incomplete, while most of them make an uninteresting game. For a four number problem, eight being the highest of these numbers, five, six, seven, and eight is the very best position from which to start the game, since its solution involves all the phases in this degree of intricacy. Thus I have discovered and in my four boards Figs. 3 to 6 inclusive, have applied the fact that the problems five, six, seven and eight; eleven, twelve, and sixteen; five, six, seven and eight; and thirteen, fourteen, fifteen and sixteen are the best suited to illustrate the beauties of the game, and for public use.

Having thus fully described my invention, what I claim is—

1. For playing a game with numbers the herein described board provided with holes or stations arranged on lines, a part of said stations being situated one on each line in proximity to each other to constitute a home or group of initial stations each having a distinct number appropriated thereto, said numbers being between proximate powers of the number 2 and said single home stations being each one of a series arranged in said line equaling in number the units of the first named station number in that line, substantially as set forth.

2. For playing a game with numbers the herein described board provided with holes or stations arranged on lines, a part of said stations being situated one on each line in proximity to each other to constitute a home or group of initial stations each having a distinct number appropriated thereto, said numbers being between proximate powers of

the number 2 and said single home stations being each one of a series arranged in said line equaling in number the units of the first named station number in that line and markers equal in number to the lines, substantially as set forth.

In testimony whereof I have signed this

specification in the presence of two subscribing witnesses.

WILLIAM HOFFMAN.
